ADJUSTABLE STAND FOR SUPPORTING REELS OR THE LIKE

Clare E. Holt, Milwaukee, Wis., assignor to Applied
Power Industries, Inc., a corporation of Wisconsin

Filed Mar. 28, 1960, Ser. No. 59,901

Term of patent 3½ years

(Cl. D41—1)

FIGURE 1 is a front perspective view taken from one side of an adjustable stand for supporting reels or the like embodying my novel design; and

FIGURE 2 is an elevational view taken from the same side as shown in FIGURE 1, on a reduced scale, the opposite side being a mirror image thereof.

The dominant features of my design reside in the portions shown in full lines.

I claim:

The ornamental design for an adjustable stand for supporting reels or the like, substantially as shown and described.
